No. 707,642.

Patented Aug. 26, 1902.

A. C. ROUNDS.

INSOLE.

(Application filed Oct. 25, 1900.)

(No Model.)

UNITED STATES PATENT OFFICE.

ALBERT C. ROUNDS, OF BUFFALO, NEW YORK, ASSIGNOR OF ONE-HALF TO
UDO V. SCHAUROTH, OF BUFFALO, NEW YORK.

INSOLE.

SPECIFICATION forming part of Letters Patent No. 707,642, dated August 26, 1902.

Application filed October 25, 1900. Serial No. 34,338. (No model.)

To all whom it may concern:

Be it known that I, ALBERT C. ROUNDS, a citizen of the United States, residing at Buffalo, in the county of Erie and State of New York, have invented new and useful Improvements in Insoles for Shoes, of which the following is a specification.

My invention relates to shoes, and more particularly to the inner soles thereof and the mode of connecting welts and uppers to such soles.

It consists of an inexpensive insole of such construction that a rigid or firm abutment is afforded to lay the welt and upper against and sew them to, said abutment being formed independent of the insole proper or body, which is advantageous, because it permits of the insole proper or body being made of textile fabric, leather-board, or other inexpensive material of even thickness throughout its width and obviates slitting of the same, and being so disposed that the inseam-stitches used to connect the welt and upper are enabled to lie close to the insole proper or body, which insures the production of an even inseam and facilitates the proper making of the shoe.

It also consists in the provision of an abutment of such character that the inseam-stitches connecting the welt and upper may be drawn in under the abutment at the outer side to remove all danger of said stitches being cut incident to the stitching of the outer or tap sole to the welt and may also be drawn in and under the abutment at the inner side to prevent them being subjected to frictional wear against the outer or tap sole.

Other advantageous features of the invention will be fully understood from the following description and claims when taken in connection with the accompanying drawings, in which—

Figure 1 is an inverted plan view, with portions partly broken away, illustrating my improved insole and a welt and upper connected thereto. Fig. 2 is a transverse section of the same. Fig. 3 is a detail transverse section illustrating a modification, and Fig. 4 is a detail transverse section illustrating the abutment and its cover included in the construction shown in Fig. 3.

Referring by letter to the said drawings,

and more particularly to Figs. 1 and 2 thereof, A is the body of my insole, which may be made of leather-board, sheet-cork, granulated cork pressed in sheets, wood, leather, pasteboard, strawboard, textile fabric, or any other inexpensive material susceptible of use as an insole-body.

B is an abutment disposed at the lower side of the body and at about the proportional distance illustrated from the edge thereof. It is essential that this abutment should be hard and firm, and it may be and preferably is a hard twisted cord made from paper, hemp, cotton, or other suitable material. When desired, however, a ratan reed, a wire, or any other suitable device calculated to afford a firm and substantial bearing for the welt to lay against may be employed. Such abutment is preferably continuous and of circular form in cross-section, as shown in Fig. 2. It may be attached to the body A by zigzag stitches, wire staples, or other suitable means, although I prefer to connect it by through-and-through vertical stitches C, arranged close together, as best shown in Fig. 2. In either case the abutment is rigidly connected to the body A—that is to say, is connected in such manner as not to have any flexible movement or lateral play.

D is a cover for the abutment B, which cover is formed of light canvas or other suitable material and is fitted snugly around the abutment and connected by adhesive or other suitable means to the under side of the body A, both without and within the abutment, as clearly shown.

E is a welt, F an upper the edges of which are interposed between the welt and covered abutment, and G G inseam-stitches which take through the welt, the upper, and the portions of the cover D at the outer and inner sides of the abutment and lie between said abutment and the body A. It is obvious that in some cases where the nature of the abutment permits the inseam-stitches may also pass through the upper portion of the abutment, as shown in Fig. 2, without altering the effect or in any way impairing the connection. It will be observed that when the inseam-stitches lie between the abutment and the body A and also when they extend through the upper portion of the abutment

they are interposed between the major portion of the abutment and the body A. In lieu of having the cover D arranged over the entire lower surface of the body A a cover 5 D', such as shown in Figs. 3 and 4, may be employed. This cover D' is applied snugly around the abutment B prior to the connection of the same to the body A, and its edge portions *a* are connected by interposed adhesive 10 or other suitable means. When the abutment thus covered is applied to the body A, it is arranged, with the edge portions *a* of the cover extending inwardly, to form a flange, as shown in Fig. 3, and is connected 15 to the body by stitches C', which take through the cover, the abutment and the body, or by other suitable means. The flange formed by the edge portions *a* of the cover is also by preference connected to the body by 20 stitches C² or other suitable means. No matter whether the cover D or the cover D' be employed, it will be observed that two thicknesses of the cover are engaged by the inseam-stitches, and consequently the cover affords 25 a strong and durable hold for said stitches. When the parts are assembled and connected in the manner described, the abutment B affords a rigid or firm and substantial bearing for the welt to lay against and one which 30 needs no reinforcement at any point. It will also be observed that by virtue of the abutment being of circular form in transverse section the inseam-stitches G may be drawn in under the abutment—*i. e.*, in between the 35 abutment and the body A—and the bights of the welt and upper may be secured below the body and within the outline thereof to effectually prevent cutting of the stitches G incident to the stitching of the outer or tap sole to 40 the welt, and may also be drawn in between the abutment at the inner side thereof and the body to prevent them being subjected to frictional wear against the outer sole during the use of the shoe. It will also be observed 45 that the inseam-stitches operate to draw the cover snugly around the abutment and securely hold it with respect thereto. Moreover, it will be observed that the abutment of circular form in cross-section affords a 50 mixed angular track of positive transit for the channel-guide of a welt-machine, and thus insures a precise and even inseam. The production of the precise and even inseam is also due in large measure to the fact that the 55 needle is guided in its movements by the under side of the insole proper or body, A,

and the inseam-stitches are carried between the abutment B and the body and engage two thicknesses of the cover D. It will also be appreciated that my improvements permit 60 of the employment of a very thin, light, and flexible body or insole proper of cheap material, since they obviate the necessity of slitting the insole proper or body.

It will be appreciated from the foregoing 65 that my improvements admit of the employment of a very cheap material for the body A and obviate the necessity of channeling, molding, lip-turning, and shaping leather strips, and all manipulations now in vogue 70 with a view of connecting welts and uppers to insoles, all of which operations are expensive and materially increase the cost of the finished product.

Having described my invention, what I 75 claim, and desire to secure by Letters Patent, is—

1. The herein-described insole for shoes consisting of the body of the same thickness throughout its width, the hard abutment 80 formed separate from the body and disposed below the same, means rigidly connecting the abutment to the body, and a cover straddling the abutment and having portions arranged adjacent to the under side of the body, where- 85 by two thicknesses of said cover will be en- gaged by inseam-stitches passed between the major portion of the abutment and the un- der side of the body.

2. The herein-described insole for shoes 90 consisting of the body of the same thickness throughout its width, the hard abutment of circular form in cross-section, formed sepa- 95 rate from the body and disposed below the same, means rigidly connecting the circular abutment to the body, and a cover straddling the abutment and having portions arranged adjacent to the under side of the body, where- 100 by two thicknesses of said cover will be en- gaged by inseam-stitches passed between the major portion of the abutment and the un- 105 der side of the body, and spaces are formed between the circular-covered abutment and the under side of the body, substantially as and for the purpose specified.

In testimony whereof I have hereunto set my hand in presence of two subscribing wit- nesses.

ALBERT C. ROUNDS.
